UNITED STATES PATENT OFFICE.

ALVIN V. ROWE, OF GALESBURG, ILLINOIS.

STEEL FENCEPOST.

Application filed November 25, 1922. Serial No. 603,219.

To all whom it may concern:

Be it known that I, ALVIN V. ROWE, a citizen of the United States, a resident of Galesburg, in the county of Knox and State 5 of Illinois, have invented new and useful Improvements in Steel Fenceposts, of which the following is a specification.

This invention has reference to steel fence posts, preferably made from a structural 10 shape such as a T bar.

Steel fence posts made from T bars are not new. Some are rolled plain and a particular wire attaching means provided, and an anchor plate riveted or otherwise attached thereto. Others are rolled with various protuberances and a special wire attaching means provided and an anchor plate applied by inserting the protuberances through openings in such plate, and the 15 protuberances then riveted down to secure the plate in place. Whatever the form has taken and in whatever manner the anchor plate has been applied it has been the aim to produce a strong, durable and inexpensive 20 post, but for one reason and another these objects have not been fully attained. I am, therefore, in the present invention to present a steel fence post of T design which obviates the objectionable features heretofore 25 countered, as will be hereinafter more fully pointed out.

My invention has for one of its objects to provide the face plate of the T bar with a plurality of spaced studs or protuberances; the studs being of similar design, and each stud being preferably wedge shape, the front face of each stud converging downwardly from a broad top shoulder to a small squared end. Forming the studs 30 in the shape of wedges on the face plate provides for their easy penetration of the ground when the post is driven, and the earth filling in above the broad shoulders at the top of each stud or wedge tends to seat 35 and lock the studs and render the removal or withdrawal of the post difficult.

The invention has for a further object to provide a new and improved fastening for an anchor plate on the post, without weakening either the post or the plate, in fact materially strengthening both. The anchor plate may be of any approved design, except that it shall have a body portion presenting an extended bearing surface on the face 50 of the post, heated before its application to the post and then given a shrinkage fit to

the post. The contraction of the metal as it cools causing the plate to firmly grip the post and become securely fastened thereon. I preferably provide the anchor plate with 60 an opening through which a stud will protrude, but which does not function as a securing means, except that the wall of the opening and one end wall of the anchor plate may have an abutting engagement with 65 studs on the post and limit endwise movement, in the event the anchor plate loosens on the post being driven.

That the invention may be more fully understood, reference is had to the accompanying drawings, forming a part of the present description, illustrating a preferred embodiment of the invention, in which:

Figure 1 is a front elevation of my improved steel fence post, partly broken away 75 and with an anchor plate attached thereto, a section of fence being shown in dotted lines;

Figure 2 is a perspective view of a portion 80 of the post;

Figure 3 is a detail face view of the post and anchor plate;

Figure 4 is a rear view of Figure 3, and

Figure 5 is a cross-section in plan as the same would appear if taken on the line 85 5-5 Figure 3.

Like characters of reference denote corresponding parts throughout the figures.

The post as made from a structural T shape includes the face plate 1 and the 90 rib or web 2. The face of the plate 1 is rolled or otherwise formed with a plurality of centrally disposed and spaced studs or protuberances 3 preferably wedge shaped, the wedges being tapered toward the lower 95 end of the post, as shown. In the rolling of the shape and the forming of the studs 3, a rib 4 is formed centrally and longitudinally of the post, which aids, as will be shown, in the holding of the anchor plate 5 100 to the post. The face of each stud 3 converges from a broad top shoulder 6 at its upper end to a small shoulder 7 at its lower end. As previously stated the wedge shape of the studs provides for their easy penetration in the ground when the post is driven, and the earth filling in above the broad shoulders at the top of each stud or wedge tends to seat and lock the studs and render the removal or withdrawal of the 105 post difficult. The shouldered ends of certain of the studs will also limit endwise 110

movement of an anchor plate, as will be explained.

The anchor plate 5 may have any suitable cross-sectional design so long as it has sufficient length and breadth to provide a good bearing surface on the post, and includes preferably a body portion 8 and wings 9 extending from either side thereof. Said plate lies in juxtaposition to the face plate 1 of the post, conforming to the rib 4 on the front thereof and gripping its side edges, and being bent over the edges of the face plate 1, as at 10, see Figure 5 in the form of a tongue and groove connection. The plate 5 has an opening 11 therethrough adapted to be passed over a stud 3 on the post; such opening conforming substantially to the shape of the stud, but large enough to allow for play of the plate on the post. The plate 5 is of such depth that when it is applied to a post with a stud 3 passing through the opening 11 in the plate, the upper edge of the plate is spaced a little below the lower end of the next and succeeding stud, and the lower edge of the plate preferably rests on the upper end of the next and succeeding stud. The plate 5 preferably has a shrinkage fit on the post, being first heated and when heated applied to the post, the body 8 thereof being pressed to conform to the rib 4 on the face plate of the post, and the said body also bent over and around the edges of the face plate 1 of the post. As the plate 5 cools it will shrink and as a result becomes firmly fastened on the face plate 1 of the post. If, however, the anchor plate should become loose on driving the post it can only have endwise movement, and this is limited by the play in the slot 11 and the upper edge of the plate 5 engaging with the lower shouldered end of the next and succeeding stud.

In Figure 1, dotted lines disclose a section of a fence attached to a post. The line wires A are attached by some suitable staple fastener B, and the line wires as well as the staples are held against downward movement, should pressure be applied to the wires in that direction, by the broadened shoulders on the upper ends of the studs 3.

What I claim is:

1. In a structure of the character described, in combination, a steel post provided with a longitudinal web and said web provided with a plurality of spaced studs providing rests for fence wires, and an an-

chor plate having a shrinkage fit on said post and the web thereon and provided with an opening to receive a stud.

2. In a structure of the character described, in combination, a steel post formed with a plurality of spaced wedge shaped studs providing rests for fence wires, and an anchor plate having a shrinkage fit on said post and formed with earth engaging portions extending on either side thereof. 60 65

3. In a structure of the character described, in combination, a steel post having a face plate provided with a longitudinal web and said web provided with a plurality of spaced wedge shaped studs providing rests for fence wires, and an anchor plate having a shrinkage fit on said face plate and the web thereon and provided with an opening to receive a stud. 70 75

4. In a structure of the character described, in combination, a steel post of structural T shape, the face plate of which is formed with a plurality of spaced wedge shaped studs providing rests for fence wires, 80 and an anchor plate having a shrinkage fit with the opposite edges of said face plate and formed with earth engaging portions extending on either side of said plate.

5. In a structure of the character described, in combination, a steel post having a face plate provided with a plurality of spaced studs to receive fence wires, and an anchor plate having a shrinkage fit on said face plate and provided with an opening to 85 receive a stud, longitudinal movement of the anchor plate on said post being prevented by the next adjacent stud above said anchor plate. 90

6. A steel fence post having a face plate 95 provided with a centrally disposed longitudinal web, and said web having formed thereon a plurality of spaced wedge shaped studs which are tapered toward the lower end of the post and providing rests for fence 100 wires.

7. In a structure of the character described, in combination, a steel fence post provided with a face plate having a central longitudinal web, and an anchor plate having a shrinkage fit on said face plate and the web thereon. 105

In witness whereof, I have hereunto affixed my hand this 11th day of November, 1922.

ALVIN V. ROWE.
